CASING FOR A PNEUMATIC VEHICLE IMPACT BUMPER

Wilbur L. Hiatt, 4508 Commonwealth Drive, Williamsburg Apt. N., Indianapolis, Ind. 46220

Filed May 6, 1971, Ser. No. 141,077

Term of patent 14 years

Int. Cl. D12—16

U.S. Cl. D14—6

Fig.1.

Fig.2.

Fig.3.

Fig.4.

Fig.5.

FIG. 1 is a front elevation of a casing for a pneumatic vehicle impact bumper of the present invention.

FIG. 2 is a rear elevation of the structure illustrated in FIG. 1.

FIG. 3 is a top plan view of the structure illustrated in FIGS. 1 and 2.

The surface texture is shown fragmentarily for convenience of illustration only.

FIG. 4 is a side elevation of the structure illustrated in FIGS. 1, 2 and 3.

FIG. 5 is an enlarged vertical section taken along the line 5—5 of FIG. 3 in the direction of the arrows.

The bottom plan view of the structure is the same as FIG. 3.

The side of the structure opposite to the side illustrated in FIG. 4 is the mirror image of FIG. 4.

I claim:

The ornamental design for a casing for a pneumatic vehicle bumper, as shown and described.
